CLAIM

The ornamental design for a front end portion of an apparatus for distributing granular material within a container, as shown and described.

DESCRIPTION

FIG. 1 is a front perspective view of the apparatus showing my design;

FIG. 2 is a front elevational view of the front end portion shown in FIG. 1, it will be understood that the flat blade element of the front end portion is substantially planar;

FIG. 3 is a top plan view of the front end portion shown in FIG. 1;

FIG. 4 is a rear elevational view of the front end portion shown in FIG. 1; and,

FIG. 5 is a bottom plan view of the front end portion shown in FIG. 1.

The broken line showing in all views of the rear portion of a front end portion of an apparatus for distributing granular material within a container is for illustrative purposes only and forms no part of the claimed design.
